UNITED STATES PATENT OFFICE

158,418

GRAPEFRUIT CORER OR SIMILAR ARTICLE

Harriet Stachowiak, Los Angeles, Calif.

Application September 7, 1948, Serial No. 148,488

Term of patent 7 years

(Cl. D89—1)

To all whom it may concern:

Be it known that I, Harriet Stachowiak, a citizen of the United States, residing in Los Angeles, in the county of Los Angeles, State of California, have invented a new, original, and ornamental Design for a Grapefruit Corer or Similar Article, of which the following is a specification, reference being had to the accompanying drawing, forming a part thereof.

I claim:

The ornamental design for a grapefruit corer or similar article, as shown.

HARRIET STACHOWIAK.
